his Attorney.

UNITED STATES PATENT OFFICE

GEORGE L. SCHEEL, OF CHICAGO, ILLINOIS.

HAIR-DRYING DEVICE.

1,137,792.

Specification of Letters Patent.

Patented May 4, 1915.

Application filed September 2, 1914. Serial No. 859,751.

To all whom it may concern:

Be it known that I, GEORGE L. SCHEEL, a citizen of the United States, and a resident of the city of Chicago, county of Cook, and State of Illinois, have invented certain new and useful Improvements in Hair-Drying Devices, of which the following is a specification.

My invention relates to improvements in hair drying devices, and has for its object the production of a device of this character which will be of improved construction and efficient in operation.

The invention consists in the combinations and arrangements of parts hereinafter described and claimed.

The invention will be best understood by reference to the accompanying drawing forming a part of this specification, and in which,

Figure 1 is a top plan view of a hair drying device embodying my invention, Fig. 2 is a side elevation thereof, a portion being broken away in order to expose underlying parts, Fig. 3 is an enlarged central longitudinal section of the rearward end portion of the device, Fig. 4 is a detail section taken on line $\alpha-\alpha$ of Fig. 2, and Fig. 5 is an enlarged detail front elevation of one of the parts of the device detached.

The preferred form of construction as illustrated in the drawing comprises a comb consisting of a back 1 and teeth 2 projecting from said back, said back and teeth being formed of a single piece of sheet metal which is bent upon itself in the manner shown in Fig. 4, so as to form a chamber 3 and a passage 4 in said back extending longitudinally thereof and substantially parallel with each other. Leading from the passage 4 are branch passages 5 which communicate with the various comb teeth 2, the adjacent sides of the latter being provided with grooves 6 which communicate or register with the branch passages 5, as clearly shown in Figs. 3 and 4. Mounted in the chamber 3 is an electrical heating element 7 the function of which is to heat the comb back 1 and which in turn is adapted to heat the air forced into the passage 4, before the same is discharged through the passages 5 in the hair drying operation.

Arranged at the rearward end of the comb back 1 is a tubular extension 8 preferably a casting, the forward end of the member 8 being provided with a seat 9 for

the accommodation of the adjacent end of comb back 1, as clearly shown in Fig. 3. The conductor wires 10 of the heating element 7 terminate in connecting terminals 11 which are mounted in a suitable plug 12 of insulating material which is mounted in an angularly disposed nipple 13 formed for the reception thereof upon the member 8. The terminals 11 are adapted to be connected with any suitable source of electricity, not shown, in order to furnish electrical energy to the heating element 7. Interposed in the conductor wires 10 is also a switch 14 of any approved design, that shown in the drawing having laterally extending operating buttons 15 so arranged that when one is depressed the circuit will be closed, and when the other is depressed, the circuit will be opened.

Abutting the rearward end of the member 8 is a block 16 of insulating material and extending from said block is a tube 17 held central by engagement with a reduced extension formed upon said block, as clearly shown in Fig. 3. The parts 1, 8, 16 and 17 are fastened by means of a connecting rod 18 which extends through said parts longitudinally thereof, the forward end of said rod being provided with a head which engages against a plate 19 closing the forward end of the comb back 1, the rearward end of said rod being provided with a nut 20 which engages against a plate 21 closing the rearward end of tube 17. With this arrangement it will be seen that the various parts will be securely clamped together by simply tightening the nut 20.

Rotatably mounted upon the tube 17 is a nipple or collar 22 held against longitudinal movement between block 16 and a collar 23 which is secured to the rearward end of said tube. The member 22 is yieldingly held in position of rotary adjustment by means of spring pressed balls 24 which are mounted in the front end of said member 22 for engagement with recesses or sockets 25 formed in the adjacent face of block 16. All of said balls and recesses are positioned the same distance from the center of rotation of said parts so that during relative rotary movement of the parts, said balls will be moved to successively engage with the various recesses, as will be readily understood. With this arrangement then, it will be seen that the parts 16 and 22 may be rotatably adjusted to various relative positions in which

the same will be automatically yieldingly locked.

The passage 4 is extended as shown through the member 8 and leading from the 5 rearward end of said member is a tube 26 held against longitudinal movement by reason of the flanged forward end of said tube engaging against the front side of block 16 and a stop collar 27 provided upon said tube 10 which engages against the outer side of plate 21. Embracing the flared rearward end of tube 26 is a compressible rubber bulb 28 provided at its opposite ends with inlet and outlet openings 29 and 30 respectively which are 15 governed by flap valves 31 and 32 respectively, so that upon flexing of the bulb 28, air will be drawn through the opening 29 and discharged through the opening 30 into the tube 26 and thence into the passages 20 4 and 5. Secured to the member 23 is a handle piece 33 the rearward end of which is curved for cooperation with the bulb 28, said member 33 serving also as a 25 guard for said bulb so as to prevent injury thereto.

In use, the device is held by the hand with the palm resting against the member 33 and the fingers engaging the bulb 28. The terminals 11 being connected with a source of 30 electrical energy, when it is desired to operate the device, one of the buttons 15 of the switch 14 is depressed to close the circuit through the heating element 7. The heating element 7 will cause the adjacent walls of 35 the chamber 3 to become heated and which in turn through conductivity will cause heating of the walls surrounding the air passage 4. Through successive flexing or depression of the bulb 28, air will be pumped through 40 the passages 4 and 5, the air while passing through passage 4 being heated through contact with the heated walls of said passage, as will be readily understood. The hot air which issues from the openings 5 coming in 45 contact with the hair will serve to effectively dry the same, as will be understood. Through the tapering formation of the passage 4, a uniform discharge through all of the openings 5 will be insured, the result without this 50 tapering formation, being to secure a high pressure at the openings 5 close to the member 8 and a very low or no pressure at the remote openings. Through the tapering formation the discharging air passage 55 through the passage 4 will be concentrated gradually toward the outer end of said passage with the result of a uniform pressure at the discharge openings 5 being secured, as above mentioned. The provision of a passage 60 for the air separate from the passage or chamber in which the heating element is employed removes all impediment from the air passage and therefore insures a more ready discharge of the air in the operation 65 of the device. Through the rotary adjust-

ment which is afforded member 22, handle piece 33 which is connected with the member 22 may be adjusted relative to the comb teeth 2 so as to secure any desired angularity of the comb teeth relative to 70 said hand piece in the operation of the device. This is of special advantage since different parts of the hair are more readily combed with the comb teeth positioned at certain angles.

While I have illustrated and described the preferred form of construction for carrying my invention into effect, this is capable of variation and modification without departing from the spirit of the invention. I, 80 therefore, do not wish to be limited to the precise details of construction set forth, but desire to avail myself of such variations and modifications as come within the scope of the appended claims.

Having described my invention what I claim as new and desire to secure by Letters Patent is:

1. In a device of the class described, the combination of a comb comprising a back having an air passage and an adjacently positioned chamber formed therein; teeth projecting from said back, there being branch air passages leading from said first mentioned air passage to said teeth; a heating element 90 mounted in said chamber; and means connected with said comb for forcing air through said air passages, substantially as described.

2. In a device of the class described, the combination of a comb comprising a back; teeth projecting from said back, there being a longitudinally extending air passage formed in said back tapering toward its outer end and branch passages leading from 100 said first mentioned passage to said teeth; a heating element mounted adjacent said air passage; and means connected with said comb for forcing air through said air passages, substantially as described.

3. In a device of the class described, the combination of a comb comprising a back; teeth projecting from said back, there being a longitudinally extending air passage formed in said back tapering toward its outer end and branch passages leading from 110 said first mentioned passage to said teeth; electrically operated means for heating said comb back; and means connected with said comb for forcing air through said air passages, substantially as described.

4. In a device of the class described, the combination of a comb formed of a single piece of sheet metal bent upon itself to form a back; teeth projecting from said back; a longitudinally extending air passage in said back and branch passages leading from 120 said first mentioned passage to said teeth; a heating element mounted in said back; and means connected with said comb for pump- 125

ing air through said air passages, substantially as described.

5. In a device of the class described, the combination of a comb formed of a single piece of metal bent to form a back; teeth projecting from said back; a longitudinally extending air passage in said back and branch passages leading from said last mentioned passages to said teeth; grooves in 10 the sides of said teeth communicating with said branch passages; a heating element mounted in said back adjacent said first mentioned passage; and means connected with said comb for forcing air through said 15 air passages, substantially as described.

6. In a device of the class described, the combination of a comb formed of a single sheet of metal bent upon itself to form a back; teeth projecting from said back; a 20 longitudinally extending air passage in said back and branch passages leading from said first mentioned passage to said teeth; an electrically operated heating element mounted in said back; a switch for closing and 25 opening the circuit through said heating element; manually operable means connected with said comb for forcing air through said passages; and an insulator interposed between said last mentioned means and said 30 comb, substantially as described.

7. In a device of the class described, the combination of a comb comprising a back having an air passage and a chamber formed therein; teeth on said back having 35 branch passages communicating with said first mentioned passage; a heating element mounted in said chamber; an extension at the rearward end of said comb back formed of a plurality of sections arranged side by 40 side; means extending longitudinally of said comb and said extension binding the various parts together; and means for forcing air through said air passages, substantially as described.

45 8. In a device of the class described, the combination of a comb comprising a back having an air passage and a chamber formed therein; teeth on said back having branch passages communicating with said 50 first mentioned passage; a heating element mounted in said chamber; an extension at the rearward end of said comb back formed of a plurality of sections arranged side by side; a connecting rod extending longitudinally of said comb and said extension binding the various parts together; and means for forcing air through said air passages, substantially as described.

9. In a device of the class described, the 60 combination of a comb comprising a back having an air passage and a chamber formed therein; teeth on said back having branch passages communicating with said first mentioned passage; a heating element 65 mounted in said chamber; a handle piece

connected with the rearward end of said comb for relative rotary adjustment; means for releasably locking said parts in positions of relative rotary adjustment; and means for forcing air through said air passages, 70 substantially as described.

10. In a device of the class described, the combination of a comb comprising a back having an air passage and a chamber formed therein; teeth on said back having 75 branch passages communicating with said first mentioned passage; a heating element mounted in said chamber; a handle piece connected with the rearward end of said comb for relative rotary adjustment; spring 80 pressed members provided in one of the adjustable parts adapted to yieldingly engage with recesses provided in the other of said parts to releasably lock said parts in positions of relative rotary adjustment; and 85 means for forcing air into said air passages, substantially as described.

11. In a device of the class described, the combination of a comb comprising a back having an air passage and a chamber 90 formed therein; teeth on said back having branch passages communicating with said first mentioned passage; a heating element mounted in said chamber; a handlepiece connected with the rearward end of said 95 comb for relative rotary adjustment; spring pressed balls provided in one of the adjustable parts adapted to yieldingly engage with sockets provided in the other of said parts to releasably lock said parts in positions of relative rotary adjustment; and 100 means for forcing air into said air passages, substantially as described.

12. In a device of the class described, the combination of a comb comprising a back 105 having an air passage and a chamber formed therein; teeth on said back having branch passages communicating with said first mentioned passage; a heating element mounted in said chamber; a tubular extension at the rearward end of said comb back; a block of insulating material abutting the rearward end of said extension member; a 110 nipple abutting the rearward side of said insulation block; a binding element securely connecting said parts; and means at the rearward end of said nipple for forcing air into said passages, substantially as described.

13. In a device of the class described, the combination of a comb comprising a back having an air passage, of a chamber formed therein; teeth on said back having branch passages communicating with said first mentioned passage; a heating element 120 mounted in said chamber; a tubular extension at the rearward end of said comb back; a block of insulating material abutting the rearward end of said extension member; a 125 tube abutting the rearward side of said in- 130

sulation block; a binding element securely connecting all of said parts; a nipple rotatably adjustable upon said tube; a handle piece on said nipple; and compressible means arranged adjacent said handle piece for forcing air through said passages, substantially as described.

In testimony whereof I have signed my name to this specification in the presence of two subscribing witnesses.

GEORGE L. SCHEEL.
